UNITED STATES PATENT OFFICE.

EDMUND WILLSON ROBERTS, OF CINCINNATI, OHIO, ASSIGNOR OF ONE-HALF TO C. S. SOMERVELL, OF RIVERTON, NEW JERSEY.

IMPACT TOOL.

Application filed August 13, 1920. Serial No. 403,194.

To all whom it may concern:

Be it known that I, EDMUND WILLSON ROBERTS, a citizen of the United States, and a resident of Cincinnati, county of Hamilton, State of Ohio, have invented certain new and useful Improvements in Impact Tools, of which the following is a specification.

My invention relates to that type of drill 10 or hammer in which a piston or plunger reciprocates within a suitable cylinder and strikes the end of a drill bit, chisel, riveting die, or other tool, at the end of its outward stroke; the movement of the piston 15 being effected by the impulse of an explosive force. The piston with the enclosing cylinder embodying my invention constitutes an engine of the two-cycle type, in which an explosion takes place at one end of the 20 piston's stroke.

One object of my invention is to provide a hand tool, of the impact type, with simple and effective means for imparting a blow to a drill bit, chisel, or the like; such means, 25 in the form of a relatively free piston or plunger, being driven by an explosive force.

A further object of my invention is to provide means for returning the blow-imparting piston or plunger after it has delivered the blow and for this purpose I have arranged rotative camming means that will impart return movement to said piston or plunger simultaneously with such rotative movement.

33 A further object of my invention is to provide a rotor arranged to rotate on the axis of the blow-imparting member; said rotor comprising a fly-wheel and the camming means whereby said blow imparting member is retracted on the non-explosive stroke.

45 A further object of my invention is to arrange the fly-wheel so that its rotative movement will effect cooling of the cylinder; the fly-wheel having its spokes set at an angle in the form of fan blades so as to draw a strong current of air over the outer wall of the cylinder.

50 And a still further object of my invention is to arrange the necessary details of construction whereby the reciprocal movements of the piston and the rotative movements of the camming means will be effected in proper order.

55 These and other features of my inven-

tion are more fully described hereinafter; reference being had to the accompanying drawings, in which:

Figure 1, is a sectional elevation of one form of impact tool embodying my invention; taken on the line I—I, Fig. 2.

Fig. 2, is a view in elevation of my improved impact tool, partly in section on the line II—II, Fig. 1.

Figs. 3, 4 and 5, are diagrammatic views, 65 showing the piston and camming means which I employ to move the piston in one direction, in several positions assumed during the operation of the tool.

Fig. 6, is a side view, partly in section, 70 of the fly-wheel, and

Figs. 7 and 8, are cross sectional views on the lines VII—VII and VIII—VIII, Fig. 1.

In Figure 1, which shows a longitudinal section of my improved impact tool, the 75 cylinder is indicated generally at 1. This cylinder may be in one piece, with a handle 2 at one end of the same and, if desired, this handle may be a separate piece properly attached to the cylinder. The bore of the 80 cylinder may be of uniform diameter throughout its length, and it may be counterbored and tapped at each end to receive the cylinder heads 3 and 4, hereinafter described.

The piston is indicated at 5, and may be made of any suitable metal, cylindrical in contour, bored longitudinally at 6, for the passage of an explosive mixture and bored transversely to receive a cross-head 90 7, which may be tapered, the ends of the same projecting beyond the surface of the piston, as indicated at 7^a. In addition this cross-head may be bored at 7^b, in line with the bore 6 of the piston, to provide an uninterrupted passage for the explosive mixture.

Surrounding the cylinder is the rotor 100 which includes a fly-wheel 8, having a hub 9, mounted on suitable anti-friction bearings, which may comprise cones 10 and 10^a carried by said hub, and cones 11 and 12 carried by the cylinder 1, with interposed balls 13; the cone 12 being threaded on the cylinder and maintained in the desired position by a locking ring 14. Attached to the interior of the fly-wheel hub 9, in any suitable manner, or forming part of the latter, are a pair of cam members, 15 and 16, between which is formed a cam groove 17, 110

with which the projecting ends 7^a of the cross-head 7 cooperate; said cam members being more clearly shown in Fig. 2, and in the diagrammatic views, Figs. 3, 4 and 5.

5 The handle end of the cylinder receives the head 3 which may be held in place by a hollow screw 18, and packed by means of a gasket 19. The upper end of the piston 5 is threaded to receive a valve cage 20, 10 screwed in place, such valve cage carrying a valve 21, which is held to its seat by a spring 22. I have arranged the cross-head 7 at or near the center of the piston with its projecting ends 7^a extending through longitudinal slots 23 formed in the walls of the cylinder and into the groove 17 formed between the cam members 15 and 16, for the purpose of imparting motion to said cam members and through the latter to the fly-wheel 8, during the forward movement of the piston, due to the force of the explosion, and for the added purpose of imparting return motion to the piston due to the kinetic energy stored in the fly-wheel, as 20 hereinafter described.

The opposite end of the cylinder receives the head 4, which may be screwed tightly into place, and this head may be bored to closely fit the end of a tool or drill shank 25, which may be held to the head by a spring yoke 26; the latter engaging pins 27 carried by the head 4. A spring 28 may be interposed between the head 4 and a shoulder 29, carried by the tool shank, and 30 the pressure exerted against said shoulder 29 by the spring 28 will normally force this shoulder against the yoke 26.

In the position referred to, that is with the shoulder 29 held by the spring 28 against the yoke 26, the inner end of the tool or drill shank 25 will be flush with the inner end of the head 4, and beyond the end of the piston when the latter is at the extreme end of its power stroke. When pressure 40 is exerted by the operator pressing the tool against its work, however, such tool is forced inward against the spring 28 until it assumes the position shown in Fig. 1, with the shoulder 29, in contact with the outer 45 end of the head 4. When in this position, the inner end of the tool will be in position to be struck by the piston at the end of its power stroke, as hereinafter described. The operator may, by varying the pressure 50 of the tool against its work, vary the extent to which the tool is forced into the cylinder, and thus control the force of the blow struck by the piston. In other words, the greater the pressure brought to bear upon 55 the tool, the more powerful will be the blow struck by the piston.

The outer wall of the cylinder, immediately surrounding the combustion chamber, is grooved at 30, providing ribs 31, for 60 air cooling. Surrounding these ribs and

flared to extend over the fly-wheel is a protective hood, which may comprise an inner shell 32, an outer shell 32^a, and an interposed body of suitable insulating material, such as magnesia, asbestos, or other similar substance, indicated at 33. This hood may be frictionally held to the cylinder or secured by any suitable fastening means. On the opposite side of the fly-wheel I may also place a protective member of reticulated or 70 foraminous material; perforated metal, for instance, as indicated at 34, which may be held in place by fastening means such as indicated at 35. Openings 36 may be provided in the head 3 to permit air to be 80 drawn therethrough for cooling the same and a spark plug 37, carried thereby. Air is drawn through these openings 36, and through the passages formed by the grooves 30 between the ribs 31 and the hood, by 85 means of bladed spokes 8^a carried by the fly-wheel 8.

A mixing valve is indicated at 38, and while this arrangement is entirely practicable for use with my improved impact tool, 90 it is obvious that any suitable form of carbureting device may be employed in lieu thereof, hence I do not wish to confine myself to any particular form of fuel feeding or mixing device. I have shown the handle 95 as provided with a lever 39 for controlling a throttle valve 40; said lever being connected with the valve by means of a controlling wire 41, which may lie in a groove 42, formed in the outer wall of the cylinder. 100

I may provide my improved impact tool with a timing device for the sparking operation, comprising an insulated ring 43, of fibre or other suitable material, carried by the hub of the fly-wheel and having a pair 105 of metal contacts 44; the cylinder being provided with an insulated ring 45, of fibre or other suitable material, having a spring-controlled member 46, for engagement with said metal contacts. 110

In the operation of my improved impact tool, the explosive mixture is drawn from the mixing valve 38 (when used), on the return stroke of the piston. On the power stroke of the piston, the mixing valve 38 is closed, and the mixture may be compressed to a pressure of approximately ten pounds per square inch. Just before the completion of this stroke, the piston uncovers exhaust ports 47, and the spent gases from the previous explosion escape to the atmosphere. As soon as the pressure in the space between the piston and the head 3 falls below that in the portion of the cylinder at the opposite end of the piston, the valve 21 will be opened, admitting a fresh charge through said valve to the explosion or working end of the cylinder. On the return stroke of the piston, the valve 21 closes, the mixture is compressed and subsequently ig- 120 125 130

nited by means of a spark between the terminals 48 of the spark plug 37. The force of the ensuing explosion imparts the power stroke to the piston, completing the cycle 5 of operations, which is repeated thereafter. It should be noted that four complete strokes, or two power and two return strokes, are made by the piston during each revolution of the fly-wheel.

10 Motion during the explosion or working stroke is transmitted to the fly-wheel 8, through the cross-head 7, (the ends of which are constrained by the slots 23 to move longitudinally of the cylinder), and the cam 15 groove 17. On the completion of the explosion stroke, the inertia of the fly-wheel maintains its rotation and causes it to impart motion through the cams and projecting ends of the cross-head to return the 20 piston.

In Fig. 3, the piston is shown on its working stroke; moving in the direction of the arrow *a*. During this stroke the projecting end 7^a is being forced against the side of the 25 cam 15 at the point *x*; turning the cam in the direction of the arrow *b*, and thereby imparting a rotary motion to the fly-wheel 8, to which said cams are attached.

In Fig. 4, the piston has approached the 30 end of its outward or working stroke, (the position assumed, if the stroke were completed, being indicated by broken lines). The movement of the piston, however, has been arrested by coming in contact with 35 the end of the tool 25, which it strikes forcibly. It will be noted that were the cam groove 17 at this point of just sufficient width to permit the passage of the projecting end 7^a, the force of the blow would react 40 upon the entire structure of the drill. In order to permit the shortening of the piston stroke without reaction upon the structure, the cam groove is made wider at this point; the distance *y* between opposite sides of the 45 groove being greater than the sum of the diameter of the projecting end and the distance *w* to which the stroke of the piston is shortened due to striking the end of the tool 25. Hence, for reasons set forth, the 50 piston is free of all restraint by the cams at the moment of striking the tool.

It is recognized that there will be a certain amount of rebound to the piston at the 55 moment of striking the tool, which would cause the projecting end to strike the upper side of the cam groove, were the cam 12 stationary at that moment. However, owing to the fact that the cam is turning rapidly, due to the inertia of the fly-wheel, the 60 projecting end will not strike the side of the groove but will pass up the groove toward the position shown in Fig. 5, which shows the relative position of the piston and cams during the return or compression stroke of 65 the piston. During this stroke, after the

inertia due to the rebound of the piston from the tool has been spent, the inertia of the fly-wheel causes the cam 15 to exert pressure against the side of the projecting end at the point *z*. Since the projecting end is 70 restrained in its motion rectilinearly, the pressure exerted by the cam forces the piston in the direction of the arrow *c* causing it to complete its compression stroke.

It will be recognized, of course, that so 75 long as there is a continuous series of explosions, tending to impart power strokes to the piston, the projecting end 7^a is in contact with the cam 15; the cam 16 being brought into contact with the projecting end 80 only when the fly-wheel is being turned by hand, preliminary to and during starting.

To recapitulate, the movement of the piston during the explosion stroke is shown in 85 Fig. 3, with the piston imparting motion to the fly-wheel 8 through the medium of the projecting end of the cross-head 7; pressing against the cam 15 at the point *x*. The position of the piston at the moment of striking the tool 25, is shown in Fig. 4, at which time 90 the piston is free from all other restraint than that due to the tool itself. The return movement of the piston during the compression stroke is shown in Fig. 5, with the fly-wheel 95 imparting movement, due to its kinetic energy, to the piston through the cam pressing against the projecting end at the point *z*.

The construction of my improved impact tool is primarily that of a two-cycle explosion engine, adapted to the purpose herein 100 set forth. In comparing it to an ordinary base-compression, two-cycle engine, it may be said that the space between the working end of the piston, the head 4, and the end of the tool 25, corresponds to the crank-case of 105 the ordinary engine. The passage through the piston corresponds to the by-pass or transfer port; the explosion chamber being similar to that of an ordinary engine.

The advantages of my construction lie in 110 its simplicity and in the fact that the gases passing through the centre of the piston assist in cooling the same, and that at the same time, it warms the explosive mixture. Another advantage is that the mixture enters 115 the centre of the combustion chamber, while the exhaust passes from ports piercing the walls of the cylinder all around the same. A further advantage in this construction lies in the fact that the piston at the moment of 120 striking the tool is free from restraint, and no springs or other cushioning devices are required and therefore the full force of the explosion, less the slight amount required to move the fly-wheel and to overcome the friction of the piston against the cylinder walls, is exerted against the tool. In this manner, the action of this structure corresponds very closely to that of the ordinary air drill or riveting hammer. Great simplicity is se- 130

cured because of the fact that the machine as arranged avoids the use of a connecting rod and crank-shaft, the function ordinarily performed by these parts being taken care of 5 by the cam members carried by the fly-wheel. I secure compactness in arranging the fly-wheel to surround the cylinder, and a further advantage lies in the avoidance of excessive weight by omitting the connecting 10 rod and crank-shaft.

A further advantage lies in the fact that the piston makes two complete cycles to one revolution of the fly-wheel, instead of two strokes as in ordinary engines, and thus a 15 rapid movement of the piston is realized without excessive speed of the fly-wheel. Another advantage lies in the fact that the tool is held momentarily out of contact with the piston which is free to move without 20 striking except at the movement that the operator presents the tool to the work, and the method of placing the tool in an operative position is a perfectly natural one; pressure being applied by the operator pressing 25 the drill against the work. A still further advantage lies in the fact that the operator can control the force of the blow by varying pressure exerted against the tool.

No ignition system other than a spark 30 plug is shown in the drawings, since it is obvious that various forms of ignition devices may be employed, and I do not wish to limit myself to the use of any particular form.

35 I claim:

1. The combination in an impact tool, of a cylinder having a longitudinal slot therethrough, a tool-bit operatively connected to one end of said cylinder, a piston longitudinally movable therein and arranged to strike said tool-bit at one end of its stroke, means for imparting striking movement to said piston by an explosive force, a cross-head carried by said piston and having an end projecting through said slot beyond the outer surface of the cylinder, a cam rotatably mounted with respect to said cylinder and encircling the same; said cam cooperating with the projecting end of said cross-head, and a fly-wheel operatively connected with said cam; said cam and cross-head being arranged to convert the rectilineal movement of said piston into rotary movement of said fly-wheel whereby the latter may retract said piston after each power stroke. 45

50 2. In a portable impact tool, the combination of a cylinder having a longitudinal slot therein, a blow-imparting piston member therein, a fly-wheel member rotatably mounted on said cylinder and encircling the same, an operative connection including a cam carried by one of said members and a cross-head carried by the other of said members and extending through said slot whereby movement may be transmitted to said fly-

wheel member from said piston member, and a tool yieldingly connected to said cylinder and successively struck by said piston-member at the ends of its power strokes, said fly-wheel member being operative to momentarily disengage said cam and said cross-head when the working stroke of said piston member is less than a full stroke. 70

3. In a portable impact tool, the combination of a cylinder having a longitudinal slot therethrough, a blow-imparting piston therein, a fly-wheel rotatably mounted on said cylinder and encircling the same, an operative connection including a cam carried by the fly-wheel and a cross-head carried by the piston and extending through said slot whereby motion may be transmitted to said fly-wheel from said piston, and a tool yieldingly connected to said cylinder and successively struck by said piston at the ends of its power strokes, said fly-wheel being operative to momentarily disengage said cam and said cross-head when the working stroke of said piston is shortened by the impact thereof with said tool. 75

4. In a portable impact tool of the explosive type, the combination of a cylinder having a longitudinal slot therethrough, a blow-imparting piston reciprocable in said cylinder, a fly-wheel encircling the cylinder, an operative connection between said piston and said fly-wheel including a cam and a cross-head having a projecting end extending through said slot and beyond said cylinder into engagement with said cam, and a tool carried by said cylinder and arranged to be struck by said piston at the end of the working stroke, said cam being momentarily carried by said fly-wheel out of operative engagement with said cross-head when the forward stroke of the piston is shortened by the impact thereof with said tool. 95

5. In a portable impact tool a cylinder, a blow-imparting piston reciprocable in said cylinder, a rotor surrounding said cylinder and rotatable with respect to the same, bearings for said rotor surrounding said cylinder, a valve for admitting fuel to said cylinder, and a control wire for operating said valve; said wire passing between said rotor and its bearings and the wall of said cylinder. 105

6. The combination, in a portable impact tool, of a cylinder, a tool-bit slidably mounted in one end of said cylinder and projecting into the chamber of the same, a blow-imparting piston longitudinally movable in said cylinder, provision for imparting striking movement to said piston by an explosive force whereby the piston is brought into forcible engagement with said tool-bit, a cross-head carried by said piston and having an end projecting through the wall of said cylinder and operative to prevent relative rotary movement between said piston 110 and the cylinder. 120

125 130

- and cylinder, a cam surrounding said cylinder and cooperating with the projecting end of said cross-head and a fly-wheel encircling the cylinder and operatively connected with said cam; said cam and cross-head being arranged to convert the rectilineal movement of said piston into rotary movement of the fly-wheel, whereby the latter retracts said piston after each power stroke.
- 10 7. In a portable impact tool, the combination of a cylinder, a tool-bit disposed at one end of said cylinder and projecting into the chamber of the same, a blow-imparting piston movable in said cylinder at a substantially constant speed throughout its stroke under the action of an explosive force for successive impacts against said tool-bit, a rotor having a cam and journaled on and surrounding said cylinder and rotatable with respect to the same, and cooperating means carried by the piston and rotor for preventing relative rotary movement between said piston and cylinder and for converting the rectilineal movement of the piston into rotary movement of the rotor, whereby the latter retracts said piston after each power stroke, said piston being free to rebound slightly at the moment of impact out of engagement with said rotor.
- 20 8. In a portable impact tool, the combination of a cylinder, a tool-bit yieldingly mounted in the end of said cylinder, a blow-imparting piston longitudinally movable in said cylinder, provision for forcibly moving said piston in one direction by an explosive force, a cross-head carried by said piston and having an end projecting through the wall of the cylinder, a rotor surrounding said cylinder and provided with a cam for cooperation with the projecting end of said cross-head, said cam and cross-head being arranged to convert the rectilineal movement of said piston into rotary movement of said rotor and the rotary movement of the latter into rectilineal movement of the piston after the piston has engaged the tool-bit, said cam being so designed as to permit rebound of the piston without interference of the cam with said cross-head.
- 30 9. In a portable impact tool, the combination of a cylinder having a bore therethrough, a piston reciprocable therein, a hammer-head unitary with said piston and slidably fitting the bore of said cylinder, a tool-bit mounted in one end of said cylinder for engagement by said hammer-head, a fly-wheel surrounding said cylinder and rotating with respect to said cylinder, and cooperating means including a cross-head carried by said piston, a cam carried by said fly-wheel and engaged by said cross-head, and a guide in said cylinder in which said cross-head travels and operative to prevent relative rotation of said piston with respect to said cylinder, said cooperating means be-

ing operative to convert rectilineal movement of said piston into rotary movement of said fly-wheel and vice-versa, said piston being impelled by an explosive force at an undiminished speed up to the moment of its impact with said tool-bit and being free to rebound and momentarily break the engagement of said cam and said cross-head at the moment of impact.

10 7. In a portable impact tool, the combination of a cylinder, a tool-bit slidingly mounted in one end of said cylinder, a blow-imparting piston longitudinally reciprocable in said cylinder, a cross-head carried by said piston, the walls of said cylinder being longitudinally slotted to guide the projecting end of said cross-head and to prevent relative rotation of said piston, a cam surrounding said cylinder for cooperation with the projecting end of said cross-head, means for impelling, by an explosive force, said piston into engagement with said tool-bit, and a fly-wheel operatively connected with said cam, said parts being arranged to convert the rectilineal movement of said piston into rotary movement of said fly-wheel and the rotary movement of the latter into rectilineal movement of the piston after the engagement of the piston with the tool-bit, said piston being out of engagement with said cam and moving with undiminished speed at the moment of impact.

11. In a portable impact tool, the combination of a cylinder, a tool-bit detachably and yieldingly mounted in one end of the same, a blow-imparting piston member reciprocable in said cylinder for impact against said tool-bit, said piston member and cylinder being restrained from relative rotary movement with respect to each other, a rotor member mounted to rotate on an axis substantially coincident with the axis of said cylinder, a cam carried by one of said members concentrically with the axis of said cylinder and a cross-head carried by the other of said members and cooperating with said cam, whereby the movement of one member is imparted to the other; the piston member being moved by an explosive force at a high rate of speed into contact with said tool-bit at the end of its power stroke and being retracted by said rotor member, said piston member being momentarily out of engagement with and clear of said rotor member at the moment of impact.

12. In an impact tool, the combination of a cylinder, a piston operating within said cylinder to compress an explosive mixture during the working stroke and to transfer the same to the head end of the cylinder at the end of the said working stroke on the principle of a single acting two-cycle explosive engine, a hammer rigid with said piston and moving as one therewith, a balance wheel, a cam rigidly connected to said wheel and

mounted to rotate on an axis substantially co-incident with the longitudinal axis of said cylinder and impact receiving means struck by said hammer immediately prior to 5 the end of each working stroke of said piston, said piston throughout its working stroke up to the moment of its impact against said impact receiving means being moved or impelled by an explosive force at 10 a substantially constant linear speed and being in driving engagement with said cam

to impart a substantially constant speed of rotation to said wheel, the momentum of said wheel being operative to momentarily move said cam out of engagement with said 15 piston at the said moment of impact and to then bring said cam into re-engagement with said piston to return said piston to the rearward limit of its compression stroke.

In witness whereof I have signed this 20 specification.

EDMUND WILLSON ROBERTS.
